UNITED STATES PATENT OFFICE.

WILLIAM D. McFADDEN, OF MIDDLEPORT, NEW YORK, ASSIGNOR OF ONE-HALF TO
FRANK P. BARRY, OF DETROIT, MICHIGAN.

METHOD OF AND COMPOSITION FOR PRODUCING LOCAL ANESTHESIA IN TEETH.

No Drawing.

Application filed July 22, 1922. Serial No. 576,849.

This invention relates to methods of producing local anesthesia in teeth for the purpose of filling cavities in teeth without pain to the patient, and also to a composition for use in carrying out this process.

The objects of the invention are to provide an improved process for producing complete anesthesia in the vicinity of a cavity in a tooth so that the cavity can be drilled out and filled without pain to the patient; also to provide a composition for use in cavities of teeth to produce anesthesia in the vicinity of the cavity; also to improve methods and compositions of this kind in other respects hereinafter specified.

Attempts have heretofore been made to produce anesthesia in teeth by placing anesthetic into the cavity to be filled, but none of these attempts have been successful for the reason that the anesthesia was either incomplete or else of such short duration that the effect would pass off before the drilling and filling of the cavity could be completed.

In carrying out my process, I employ a composition consisting of cocaine in dry or powder form, mixed with adrenalin or some similar derivative of the superrenal glands, in the proportions of approximately two hundred parts of cocaine to one part of adrenalin. This mixture is pressed into the form of small tablets which can be placed into the cavity of a tooth. Preferably the composition also includes a coloring matter or dye such for example as red oxide of lead, which serves the purpose of enabling a dentist to readily distinguish the anesthetic by its color from the adjoining portions of a tooth and from dental cement, since the mixture of cocaine and adrenalin without coloring matter is approximately of the same color as the teeth and cement. I have found, for example, that a tablet of the composition containing one sixth grain of cocaine hydrochloride, one twelve hundredth grain of adrenalin and trace of lead oxide, can be very successfully used, although it is not necessary to adhere to these proportions, since as much as one half grain of cocaine hydrochloride may be used and the quantity of adrenalin may be increased or decreased as desired.

In carrying out the process embodying my invention, I first clean out the cavity in the usual manner as far as possible with-

out causing any pain. The portion of the tooth in which the cavity is located is then dried and a tablet of my composition is inserted into the cavity, in dry form. The cavity with the composition in place therein is then sealed in any suitable or desired manner, dental cement preferably being used and being applied to the cavity in such a manner that all moisture will be excluded, since the composition is extremely soluble in water. Other cements or sealing materials or compositions may be used in place of ordinary dental cement, if desired. The cavity is completely sealed for a period of from two to four hours, depending upon the depth of the cavity, and after the lapse of this interval of time, the cement or other sealing material is removed from the cavity. It will be found that the moisture in the tooth has entirely dissolved the tablet and the cavity is then in condition to be drilled out and filled. During the drilling and filling operations the patient has no sensation of pain and consequently much of the dentist's time is saved in the drilling and filling of the tooth.

The anesthetic apparently acts mainly upon the minute fibrillæ of the dentine and prevents these fibrillæ from transmitting sensations of pain to the nerve of the tooth, although in the cases of a deep cavity, the nerve of a tooth may be partly affected by the anesthetic. The cocaine and adrenalin in the composition are apparently taken up by the moisture in the dentine of the tooth by osmosis and the action of the anesthetic continues for a considerable period of time, sometimes for more than an hour after the seal is removed, so that the dentist has plenty of available time in which to complete the drilling and filling of the cavity.

The cocaine in the composition has the usual effect of anesthetizing the portions adjacent thereto and the adrenalin or similar composition is used for the purpose of contracting the blood vessels in the vicinity of the cavity so as to prolong the anesthesia.

The method and composition described have the advantages that owing to the fact that the action of anesthesia is very local in its nature, no bad after-effects of any kind occur and cavities of the kind which usually cause the greatest amount of pain can be drilled out and filled without having the patient experience any pain whatever.

The absence of pain on the part of the patient makes it possible for the dentist to accomplish his work in a very much shorter space of time than is ordinarily possible. The coloring matter in the composition also aids in the work of drilling out the cavity since the presence of the coloring matter enables the dentist to readily locate the portions of the cavity which must be drilled out.

I claim as my invention:

1. The herein-described process of preparing cavities in teeth for treatment, consisting in effecting a preliminary cleaning of the cavity, inserting into the cavity a local anesthetic and adrenalin, placing over the cavity and the anesthetic and adrenalin therein a seal of dental cement to exclude moisture from the cavity, permitting the local anesthetic and adrenalin to be absorbed by osmosis by the dentine surrounding the cavity to anesthetize the tooth in the vicinity of the cavity, and then removing the seal after an interval of from two to four hours.
2. The herein-described process of preparing cavities in teeth for treatment, consisting in effecting a preliminary cleaning of the cavity, inserting into the cavity an anesthetic including cocaine and adrenalin in the proportions of approximately two hundred parts by weight of cocaine to one part of adrenalin, placing over said cavity and the anesthetic therein a seal of dental cement to exclude moisture from the cavity, permitting the cocaine and adrenalin to be

absorbed by the dentine surrounding the cavity by osmosis to anesthetize the tooth in the vicinity of the cavity, and then removing the seal after an interval of from two to four hours.

3. The herein-described process of preparing cavities in teeth for treatment, consisting in placing into a cavity a dry anesthetic including a coloring matter, covering the cavity and the anesthetic therein with a seal to exclude moisture from the cavity, and permitting the anesthetic to act for a period of from two to four hours.

4. The herein-described process of preparing cavities in teeth for treatment, consisting in inserting into the cavity an anesthetic in dry form, including cocaine and adrenalin and a coloring matter, sealing the cavity with the anesthetic therein, permitting the anesthetic to be absorbed by the dentine of the tooth adjacent to the cavity, and then removing the seal.

5. The herein-described composition for producing local anesthesia in teeth, including cocaine and adrenalin in dry form and a pigment of a color differing from that of adjacent parts of the teeth.

6. The herein-described composition for producing local anesthesia in teeth, including cocaine hydrochloride and adrenalin in dry form in the proportions of two hundred parts of cocaine hydrochloride and one part of adrenalin and sufficient oxide of lead to give the composition a reddish color.

WILLIAM D. McFADDEN.
